CLAIM

The ornamental design for a window glazing tool, as shown and described.

DESCRIPTION

FIG. 1 is a front elevation of a window glazing tool showing my new design.

FIG. 2 is a left side elevational thereof, the opposite side being a mirror image to the side shown.

FIG. 3 is a rear elevational thereof.

FIG. 4 is a bottom plan view thereof; and,

FIG. 5 is a top plan view thereof.
